UNITED STATES PATENT OFFICE.

WASHINGTON H. KILBOURN, OF GREENFIELD, MASSACHUSETTS, ASSIGNOR
TO THE KILBOURN MANUFACTURING COMPANY, OF BOSTON, MASSA-
CHUSETTS.

TRACK-SANDING DEVICE.

SPECIFICATION forming part of Letters Patent No. 624,820, dated May 9, 1899.

Application filed December 16, 1898. Serial No. 699,418. (No model.)

To all whom it may concern:

Be it known that I, WASHINGTON H. KILBOURN, of Greenfield, in the county of Franklin and State of Massachusetts, have invented
5 certain new and useful Improvements in Track-Sanding Devices, of which the following is a specification.

This invention has for its object to provide an effective device for supplying sand, salt, 10 &c., to the rails of railway-tracks and to be operated with the minimum expenditure of power.

The invention consists in the improvements which I will now proceed to describe and 15 claim.

Of the accompanying drawings, forming a part of this specification, Figure 1 represents a longitudinal section of a portion of a street-car provided with a sanding device embodying my invention. Fig. 2 represents a section on line 2 2 of Fig. 1, looking toward the left. Fig. 3 represents a section on line 3 3 of Fig. 1. Fig. 4 represents a top plan view of the sand-holder shown in the preceding 20 figures. Fig. 5 represents a perspective view showing said holder partly in section. Fig. 6 represents a sectional view of a portion of a car, showing a cam rotated by an axle of the car and connected with a sand-displacing 25 device in the sand-holder mounted on the car. Fig. 7 represents a perspective view of a sand-holder embodying a modification of my invention. Fig. 8 represents a section on line 8 8 of Fig. 7 looking toward the left. Fig. 9 represents a top view of the construction 30 shown in Fig. 7, together with means for rotating the disk-shaped shovel. Fig. 10 represents a section on line 10 10, Fig. 9. Fig. 11 represents a section on line 11 11, Fig. 10. 35 The same letters of reference indicate the same parts in all the figures.

My improved sanding device comprises a holder of any suitable construction for a body of sand, a substantially horizontal shovel, 40 which is located below and is in contact with the mass of sand, means for moving said shovel edgewise to cause it to horizontally displace a portion of the sand resting upon it, and an outlet arranged to receive the horizontally-displaced sand, the said parts being 45 relatively arranged so that when the shovel

is moved it will not experience any considerable degree of resistance from the sand above it and will horizontally displace a considerable quantity of sand and supply the same to 55 the outlet. The shovel may be of any suitable form and construction and may be moved horizontally edgewise by any desired means, and I here remark that I desire to be understood as including in the scope of my present 60 invention, so far as the first claim of this application is concerned, the reciprocating shovel shown in my pending application for Letters Patent of the United States, Serial 65 No. 695,933. I have shown in this application, and have hereinafter claimed more or less specifically, a disk-like shovel connected with the sand-holder by rotative connection, the shovel being adapted to move in a curved path on said connection and to either oscillate or rotate progressively in one direction. 70

I will first describe the construction shown in Figs. 1 to 5, inclusive, which show the shovel adapted to oscillate. In said figures, a represents the sand-holder, which is suitably secured to the body b of the car, and c represents the shovel, which is a flat plate of disk-like form located horizontally over and in close proximity to the bottom of the holder a. The rotative connection between the 80 shovel and the holder is here shown as including a sleeve d, which is affixed to the bottom of the sand-holder and projects upwardly therefrom, a socket e, affixed to the shovel c and formed to receive and turn 85 freely upon the sleeve d, and a shaft f, fixed to the upper end of the socket e and projecting downwardly through the sleeve d, said shaft being connected at its lower end with means for imparting a rocking motion to it, 90 said motion being imparted to the socket e of the shovel c, which is thus caused to oscillate or turn first in one direction and then in the opposite direction on the bottom of the sand-holder. The outlet g of the sand-holder is 95 located at one side of the center of motion of the shovel, and the shovel is cut away or recessed between the said center of motion and the outlet g, so that the edge of the cut-away portion constitutes virtually the ends of two 100 shovels, one of which delivers sand when the shovel is turned in one direction, while the

other delivers sand when the shovel is turned in the opposite direction, the result being a nearly continuous movement of sand from the holder to the outlet *g*.

5 I have shown the sand-holder provided with an inclined guard-plate *h*, the lower edge of which is separated from the shovel *c* by a narrow space or throat *i*, which permits the desired movement of the sand to the outlet *g* by the shovel, but is so narrow that it prevents the accidental escape of sand by gravitation when the shovel is not in use. I have also shown the holder provided with an opening *j* above the outlet *g*, the object of said opening being to permit the escape of damp air that may rise through the outlet *g* and prevent the same from affecting the body of sand in the holder.

The shaft *f* may be rocked and the shovel *c* oscillated by any suitable means. In Fig. 1 I show as the operating means a pedal *k*, arranged to be depressed by the foot of the motorman, a bell-crank lever *k'*, arranged to be moved by the pedal, and a rod *k''*, connecting the lever *k'* with an arm *k'''*, affixed to the shaft *f*. A spring *k⁴* is arranged to move the parts in a direction opposite to the motion imparted by the depression of the pedal *k*, so that when the pedal is released the shovel is turned in one direction and when the pedal is depressed the shovel is turned in the opposite direction. The fixed sleeve *d*, projecting upwardly from the bottom of the sand-holder, and the socket *e*, fitted to rotate on said sleeve, enable the shovel to be oscillated readily, the socket *e* being in contact with the body of sand above the shovel and serving to loosen the sand by its rocking movements therein.

In Fig. 6 I show means for operating a sand-displacing device in a sand-holder by power derived from an axle of the car. *m* represents the axle, and *n* a cam affixed thereto. *o* represents a lever mounted to oscillate on a fulcrum *p* and having its lower end pressed by an expanding-spring *q* against the cam *n*. The upper end of the lever *o* is connected by a rod *r* with the sand-displacing device, which may be a shovel *c* of the construction above described. When it is not desired to operate the sanding device, the lever *o* may be made inoperative by means of a slide *s*, which supports the fulcrum *p* and is movable in a fixed guide *t* by means of a lever *u*, mounted on the car-platform. A spring *v* normally acts on said slide to hold the lever *o* in the operative position. (Shown in Fig. 6.) When the lever *u* is moved from the position shown, it moves the fulcrum *p* away from the cam, thus withdrawing the lever *o* from the path of the cam. 60 In Figs. 7 to 11 I show a modification of my invention in which the shovel is given a progressive step-by-step rotation. In said figures, *a'* represents the sand-holder, and *c'* represents the shovel, which in this case is a complete disk affixed to a shaft *c²*, which is journaled in a bearing *c³* on the bottom of the

sand-holder. To the shaft *c²* is affixed a ratchet *c⁴*, with which are engaged spring-dogs *c⁵ c⁶*, carried by a bifurcated arm or rod *c⁷*, which may be operated similarly to the rod *k²* (shown in Fig. 1) or the rod *r*. (Shown in Fig. 6.) The sand-outlet *g'* is located outside the periphery of the disk-shaped shovel. The side of the holder *a'* adjacent to the outlet *g'* is provided with an opening *a²*, extending half-way across the diameter of the shovel *c'*, the said side of the holder *a'* having at the opposite side of the center of the shovel an extension *a³*, the lower edge of which is in close proximity to the upper surface of the shovel, so that the shovel, which is rotated in the direction indicated by the arrow in Fig. 7, carries the sand outwardly through the opening *a²* and moves it against the extension *a³*, the latter serving as a scraper, which causes the sand as it accumulates to flow outwardly into the outlet *g'*.

It will be seen that the shovel in each of the cases above described moves edgewise under the body of sand, and while it supports the weight of the mass of sand in the holder or the greater part of such weight by reason of its edgewise movement it displaces the sand horizontally and feeds it to the outlet with the minimum of resistance.

While I have called the displacing device *c* and *c'* a "shovel," I do not desire to be understood as limiting myself to a continuous plate or disk of metal, as a similar result would be produced if the part called a "shovel" were of open construction and were composed, for example, of a series of flat radiating arms movable edgewise. It is obvious, however, that the continuous-plate construction is preferable to any open construction, because it moves under the sand with less resistance, since it presents, when made of disk-like form, no edges to press against and be obstructed by the mass of sand.

It will be seen that by attaching the sand-displacing shovel to a vertical shaft which extends downwardly through the bottom of the sand-holder the construction of the device is rendered more compact than that shown in my above-mentioned former application, considerably less space being required on and above the bottom of the car for the sand-holder, while the operating mechanism for the displacing device is located wholly below the bottom of the car. The present improvement is therefore well adapted for use on open cars, where there is less available space above the bottom of the car than in closed cars. The opening *i* (shown in Figs. 1 and 5) and the opening *a²* (shown in Figs. 7 and 8) may be termed a "primary" outlet, the tube *g*, Figs. 1 and 5, and the tube *g'*, Fig. 7, being a secondary outlet. The function of the said primary outlet in each case is to limit the escape of sand from the holder by gravitation and prevent the sand from flowing to the secondary outlet when the shovel is not in operation.

In Fig. 1 I show the rod k^2 provided with a hammer y , arranged so that when the pedal k is released the movement of the rod k^2 by the spring k^4 will force the hammer against the outlet g , jarring the latter and dislodging any accumulation of gravel, &c., that may have formed in the outlet.

It will be observed that the sleeve d , projecting above the bottom of the sand-holder a , prevents the escape of sand around the shaft f , while the socket e , covering the sleeve d , prevents the admission of sand to the upper end of the sleeve.

I claim—

1. A track - sanding device comprising a sand-holder, a substantially horizontal shovel located in the bottom of the holder and having a flat upper surface in contact with the body of sand in said holder and movable edgewise to horizontally carry a portion of the sand above it, and an outlet arranged to receive the sand, delivered by said shovel.

2. A track - sanding device comprising a sand-holder, a substantially horizontal shovel located in the bottom of the holder and having a flat upper surface in contact with the body of sand in said holder, a rotative connection between the shovel and holder, whereby the shovel is movable edgewise in a curved path, and means for moving the shovel.

3. A track - sanding device comprising a sand-holder, a substantially horizontal shovel located in the bottom of the holder and having a flat upper surface in contact with the body of sand in said holder, a rotative connection between the shovel and holder, and means for oscillating the shovel on said connection.

4. A track - sanding device comprising a sand-holder, a substantially horizontal shovel located in the bottom of the holder and having a flat upper surface in contact with the body of sand, a rotative connection between the shovel and holder, an outlet located at one side of the shovel, the shovel being cut away or recessed between the outlet and the center of movement of the shovel, and means for oscillating the shovel.

5. A track - sanding device comprising a sand-holder having a fixed vertical sleeve or bearing, a substantially horizontal shovel having a vertical socket fitted to receive and turn on said sleeve, a shaft attached to said socket and extending through the fixed sleeve, and means for turning said shaft.

6. A track - sanding device comprising a sand-holder, a sand-displacing device therein, an outlet arranged to receive sand from the displacing device, a cam rotated by an axle of

the car, and connections between the said cam and displacing device.

7. A track - sanding device comprising a sand-holder, a sand-displacing device therein, an outlet arranged to receive sand from the displacing device, a cam rotated by an axle 65 of the car, a slide having a fulcrum which is movable toward and from the cam, a lever pivoted on said fulcrum and adapted to be moved by the cam, connections between said lever and the displacing device, and means for moving the slide relatively to the cam to make the lever operative or inoperative by the cam.

8. A track - sanding device comprising a sand-holder, a substantially vertical shaft extending through the bottom of the holder, a 75 substantially horizontal shovel affixed to said shaft within the holder and having an extended surface for supporting the mass of sand in the holder, said shovel being movable edgewise by a rotary movement of the 80 shaft, means for moving said shaft to move the shovel edgewise and cause it to displace sand horizontally, and an outlet arranged to receive the sand displaced by the shovel.

9. A track - sanding device comprising a 85 sand-holder having a primary outlet, a substantially horizontal shovel movable edgewise on the bottom of the holder and adapted to displace sand horizontally through said outlet, means for moving said shovel, and a secondary outlet located adjacent to the primary outlet and arranged to receive the displaced sand, the primary outlet being arranged to discharge sand in a direction toward said secondary outlet.

10. A track-sanding device comprising a sand-holder having a sleeve projecting upwardly into its interior from the bottom of the holder, a shaft within said sleeve extending through the bottom of the holder, a socket attached to the upper end of the shaft and covering the upper end of the sleeve, and a substantially horizontal shovel attached to the socket and located at the lower portion of the latter.

11. A track-sanding device comprising a holder, an outlet formed as a spout extending below the holder, a sand-displacing device arranged to supply sand to said spout, mechanism for operating the displacing device, and a hammer connected with said mechanism and arranged to strike the spout.

In testimony whereof I have affixed my signature in presence of two witnesses.

WASHINGTON H. KILBOURN.
